CLOTHING

Alexander Philipps, Chicago, Ill.

Application December 17, 1945, Serial No. 635,438

6 Claims. (Cl. 2—270)

1

This invention relates to clothing and more particularly to a combination mitten and sleeve.

One object of the present invention is to provide a sleeve adapted to conceal a mitten when the latter is not in use.

Another object is to provide a mitten-sleeve which is less bulky than those now in use.

A further object is to provide a mitten-sleeve which will be attractive and have a ready sale.

A still further object is to provide a mitten-sleeve which is easy to adjust.

A still further object is to provide a mitten-sleeve in which the mitten can be readily removed for cleaning.

A still further object is to provide a mitten-sleeve in which the mitten can be readily removed in moderate weather.

Other objects will become apparent upon considering the following specification which, when considered in conjunction with the accompanying drawings illustrates one form of the invention.

In the drawings:

Fig. 1 is an elevational view of the outer side of a sleeve embodying the present invention with the mitten in stored position, parts thereof being broken away to more clearly illustrate the construction;

Fig. 2 is a view similar to Fig. 1, but with the mitten in wearing position;

Fig. 3 is an elevational view of the inner side of the sleeve with the mitten in wearing position, parts being shown broken away to more clearly illustrate other parts;

Fig. 4 is a cross-section taken on the line 4—4 of Fig. 2 looking in the direction of the arrows;

Fig. 5 is a perspective view of the bottom of the sleeve;

Fig. 6 is an elevational view of the bottom of the sleeve with the finishing tab buttoned on the sleeve; and

Fig. 7 is a cross-section on the line 7—7 of Fig. 4 looking in the direction of the arrows.

Referring to the drawings, the sleeve 10 is made of coating material, suitably shaped, the sleeve being secured to the body of the coat by sewing so that the under sleeve lies adjacent the body of the wearer, the opposite side of the sleeve being termed the top sleeve.

The under sleeve is provided with a seam 11 running longitudinally of the sleeve and terminating in a cuff 12. The top sleeve is provided with a welted seam 14 which runs the length of the sleeve, the lower part of which conceals a slide fastener 16 of the type commercially known

2

as a "zipper." The fastener or "zipper" 16 is adapted to provide an opening into the lower end of the sleeve for the purpose set forth below.

The lower end of the sleeve is provided with a liner 18 which is attached to the inside of the outer coating material on the seams 11 and 14 and extends around the interior of the top sleeve from the cuff substantially to the elbow. The liner 18 and the coating material form a compartment 19, opening downwardly through the cuff of the sleeve. The compartment 19 is adapted to be opened on the side by unfastening the "zipper" 16.

A lining 20 is secured to the top of the sleeve, at the shoulder and extends downwardly to the cuff. The lining 20 is attached to the cuff of the coating material of the under sleeve between the seams and to the bottom of the liner 18 on the top sleeve.

20 A button 21 or other equivalent fastening device is secured in the bottom of the compartment 19 to both the liner and the lining to retain a mitten 22. It is to be understood that the term mitten is to be construed broadly enough to include both fingered and unfingered coverings for the hand.

The mitten 22 has a button hole 25 on the back thereof over which the button 21 is receivable so that the mitten 22 may be pivoted on the button 21 between a depending wearing position and an upstanding storage position.

The palm side of the mitten may be provided with snaps or other fasteners 28 on the outside of the mitten cuff which engage with mating snaps 30 on the interior of the under sleeve to secure that side of the mitten to the sleeve while in use.

40 A finishing tab 32 may be sewed at one end to the cuff of the sleeve and be provided with a buttonhole 35 at the opposite end of the tab. The tab 32 may then extend over the welted seam 14 and be secured to the coat on a button 38.

Operation

45 In cold or inclement weather the mitten 22 is secured to the liner 18 by buttoning it onto the button 21 with the palm toward the inside of the sleeve. The snaps 28 on the mitten are secured onto the snaps 30 on the interior of the under sleeve. Snapping the mitten onto the cuff forms a windbreak and keeps the cold air from passing up the sleeve thus aiding in keeping the wearer warm.

50 With the mitten in the above position the wearer can put on his coat and put his hand di-

rectly in the mitten in one movement. When the coat and mittens are removed they are taken off as a unit and the mittens remain in place for the next time the coat is worn.

In milder weather the tab 32 is unbuttoned and the "zipper" 16 opened, opening the side of the compartment 19. The snaps 28 on the mitten are then unfastened from the snaps 30 on the cuff and the mitten rotated on the button 21 into the compartment 19. The slide fastener or "zipper" may then be closed and the tab 32 buttoned on the button 35. In this position the mitten is out of the way, and yet available for immediate use.

In the event that it is desired to remove the mitten for cleaning or during warm weather it may be readily removed from the button 21.

It will be noted that the above construction gives a mitten sleeve which is not bulky, and one in which the mitten can not become lost, yet may be removed readily for cleaning.

It is to be understood that the form of the invention herein shown and described is to be taken merely as a preferred example of the same, and that various changes in size, shape and arrangement of parts may be made without departing from the spirit of the invention or the scope of the subjoined claims.

That which is new and is desired to be secured by Letters Patent is:

1. In a garment of the character described including a sleeve having an outer covering and a lining, stitching securing a portion of the lower end of the lining to the cuff of the sleeve, the unstitched portion and the outer covering forming a downwardly opening compartment, a button secured in the compartment to the lining, and a mitten pivotally mounted on said button and adapted to rotate on said button from a depending wearing position to an upstanding storage position in said compartment.

2. In a garment of the character described a sleeve comprising an outer coating material, a liner attached to the inside of said sleeve and extending partially around the interior thereof, said liner forming a downwardly opening compartment between the liner and the coating material, and a mitten pivotally mounted in the lower end of said compartment, said compartment being adapted to receive and conceal the mitten when not in use.

3. In a garment of the character described a sleeve comprising an outer coating material, a liner attached to the inside of said sleeve and extending partially around the interior thereof,

said liner forming a downwardly opening compartment between the liner and the coating material, a slide fastener in said sleeve adapted to open into the side of said compartment, and a mitten pivotally mounted on the lower end of the liner and adapted to be rotated through the said side opening into said compartment to conceal the mitten when not in use.

4. In a garment of the character described a sleeve comprising an outer coating material, a liner extending around the interior of the top sleeve and connected to the outer coating material by sewing on longitudinal seams, said liner forming a downwardly opening compartment between the liner and the coating material, and a mitten pivotally mounted in the lower end of said compartment, said compartment being adapted to receive and conceal the mitten when not in use.

5. In a garment of the character described a sleeve comprising an outer coating material, a liner extending around the interior of the top sleeve and connected to the outer coating material by sewing on longitudinal seams, said liner forming a downwardly opening compartment between the liner and the coating material, and a mitten pivotally mounted in the lower end of said compartment, said compartment being adapted to receive and conceal the mitten when not in use.

20 6. In a garment of the character described a sleeve comprising an outer coating material, a liner extending around the interior of the top sleeve and connected to the outer coating material by sewing on longitudinal seams, said liner forming a downwardly opening compartment between the liner and the coating material, and a mitten pivotally mounted in the lower end of said compartment, said compartment being adapted to receive and conceal the mitten when not in use.

25 7. In a garment of the character described a sleeve comprising an outer coating material, a liner extending around the interior of the top sleeve and connected to the outer coating material by sewing on longitudinal seams, said liner forming a downwardly opening compartment between the liner and the coating material, and a mitten pivotally mounted in the lower end of the liner and adapted to be rotated through said side opening into said compartment to conceal the mitten when not in use.

30 8. In a garment of the character described a sleeve comprising an outer coating material, a liner extending around a portion of the interior of the sleeve and open at the bottom thereof to form with said coating material a downwardly opening compartment, means to open the coating material to give access to the compartment from one side thereof, a lining within said sleeve and

35 9. In a garment of the character described a sleeve comprising an outer coating material, a liner extending around a portion of the interior of the sleeve and open at the bottom thereof to form with said coating material a downwardly opening compartment, means to open the coating material to give access to the compartment from one side thereof, a lining within said sleeve and inside said liner, a mitten pivoted on the lower part of the liner and snaps on the cuff of the mitten on the side of the mitten opposite the pivot co-operating with snaps on the cuff of the sleeve to secure that side of the mitten to the sleeve.
